UNITED STATES PATENT OFFICE.

WILLIAM A. COULSON, OF MOSS POINT, MISSISSIPPI.

SASH-FASTENER.

SPECIFICATION forming part of Letters Patent No. 602,731, dated April 19, 1898.

Application filed May 26, 1897. Serial No. 638,193. (No model.)

To all whom it may concern:

Be it known that I, WILLIAM A. COULSON, residing at Moss Point, in the county of Jackson and State of Mississippi, have invented 5 a new and useful Window-Lock, of which the following is a specification.

My invention is in the nature of a device for application to a window-sash whereby the sash may be freely raised and locked in any 10 raised position and all rattling of the sash is prevented.

The object of my invention is to provide a device of this class which shall be simple, cheap, and strong, easily applied, and effective in operation.

With this object in view my invention consists of an eccentric pivoted in the window-sash in such a position as to admit of the window being freely raised, but which will change 20 its position when an attempt is made to lower the window and lock the sash by forcing it against the opposite side of the frame.

My invention further consists in the improved construction, arrangement, and combination of details hereinafter fully described, and afterward specifically pointed out in the appended claims.

In order to enable persons skilled in the art to which my invention most nearly appertains to make and use the same, I will now proceed to describe its construction and operation, reference being had to the accompanying drawings, in which—

Figure 1 is a perspective view of the lower 35 portion of a window frame and sash having my invention applied thereto in position for practical operation. Fig. 2 is a view in side elevation of my improved window-lock detached from the window. Fig. 3 is a view of

40 my improved locking-plate in elevation. Fig. 4 is a sectional view through the locking-plate and the casing for the eccentric, showing the eccentric in side elevation locked into engagement with the locking-plate. Fig. 5 is

45 a transverse section through my improved lock on the line 5 5 of Fig. 2. Fig. 6 is a side elevation of my improved antirattler. Fig. 7 is a view similar to Fig. 4 of my antirattler. Fig. 8 is a detail perspective view of the eccentric having my antirattler detached.

Like letters of reference mark the same

parts wherever they occur in the various figures of the drawings.

Referring to the drawings by letters, A is the sash, and B the frame, of a window, being 55 of any ordinary or preferred construction.

C is a casing within which are contained all the operative parts of my invention. This casing may be of any desired outline—as, for instance, forming slightly more than half a 60 circle—and it may be let into the sash from the side or attached upon the face of the sash at the edge thereof.

D is a crescent-shaped metal plate which I denominate my “eccentric” from the fact 65 that it is eccentrically pivoted at D' to the casing C.

E is the main spring, secured upon a pin F at its upper end near the pivot of the eccentric and consisting of two arms, one of which 70 bears against the pin G and the other against the end of the eccentric nearest to the window-frame.

H is a hook-point extending outward and forward from the eccentric and adapted to 75 engage in an opening I in the lock-plate J, secured to the face of the window-frame.

K is a knob projecting from the eccentric through a slot L in the casing, whereby the eccentric may be operated from the outside 80 of the casing.

M is a bolt normally held in position to be engaged by the back point of the eccentric and to slip into a socket N in the eccentric by the spring O.

P is a key for withdrawing the bolt from the socket.

Q are rollers pivoted to the outer edge of my eccentric when the device is used as an antirattler.

The operation of my invention is as follows: When the window is raised, the eccentric will be moved around upon its pivot against the action of the main spring E until the shorter diameter comes opposite to the 95 window-facing, which will permit the window to be freely raised; but when an attempt is made to lower the window the eccentric will be pressed around in the opposite direction and the back point will ride behind the point 100 of the bolt M until the socket N in the eccentric comes opposite to the bolt, when the bolt

will be pressed into the socket, thus locking the eccentric in position, with the hook H engaging in the socket I of the lock-plate J. This will lock the window in the position to 5 which it has been moved, which will be depending upon the position of the lock-plate in the window-frame, the lock-plate being usually placed at the bottom of the window-frame to lock the window down. When it is 10 desired to raise the window from its locked position, the key P is turned to bring its wards into contact with the spring O, pressing said spring backward and withdrawing the bolt M from the socket N and holding it in its 15 withdrawn position. The eccentric may then be moved against the action of the main spring E by pushing the knob K to the right in the slot L (see Fig. 2) and the window raised above the locking-plate. The knob will then 20 be released, when the sash can be freely raised to any desired position, when any attempt to lower the sash will cause the eccentric to be turned to the right, thus wedging the sash firmly against the opposite side and holding 25 it in its raised position.

When it is desired to use my device as an antirattler, the rollers Q are pivoted upon the outer edge of the eccentric, and these come in contact with the sash in raising or lowering, 30 and, while permitting of the free raising thereof, being pressed against the sash by the main spring E, the lowering of the window will be retarded by reason of the partial rotation of the eccentric on its pivot, due to the contact 35 between the rollers and the frame, which will press the sash with considerable force against the opposite side of the frame.

The construction and operation of my device will be readily understood from the foregoing, and its simplicity, cheapness, and advantages are obvious. 40

While I have illustrated and described what I believe to be the best means for carrying out my invention, I do not wish to be understood as limiting myself to the exact construction and arrangement herein shown, but hold that such slight changes and modifications as might suggest themselves to the ordinary mechanic would properly fall within the limit and scope of my invention. 45 50

Having thus fully described my invention, what I claim as new, and desire to secure by Letters Patent, is—

1. The combination of a window sash and frame, with a crescent-shaped cam-faced plate eccentrically pivoted to the sash and projecting therefrom in contact with the frame, the spring pressing the lower horn of the plate toward the sash, and a spring-bolt engaging an opening in the inner or upper horn and securing the eccentric in its locked position, substantially as set forth. 55

2. The combination of the window sash and frame with a lock-plate secured to the frame and provided with a suitable socket, a plate eccentrically pivoted to the sash and having a hook to engage in said socket and a spring-bolt adapted to engage in a socket in the eccentric to fasten it in its locked position, substantially as set forth. 60 65

WILLIAM A. COULSON.
